PORTABLE RANGE AND FOOD SERVICE COMBINATION OR SIMILAR ARTICLE

Ving Smith, Westchester County, N.Y., assignor to General Electric Company, a corporation of New York

Filed Mar. 30, 1960, Ser. No. 59,959

Term of patent 14 years

(Cl. D81—10)

Figure 1 is a side perspective view of a portable range and food service combination or similar article showing my new design, taken from the range end.

The undisclosed side of the portable range and food service combination is substantially the same as the side shown except for the drawer and door.

The essential features of my design reside in the portions shown in full lines.

I claim:

The ornamental design for a portable range and food service combination or similar article, as shown and described.
